WALL FORM SYSTEM

William H. Kenney, Teaneck, N.J., assignor, by mesne assignments, to William H. Kenney, Middletown, Ohio
Filed Nov. 16, 1961, Ser. No. 152,830

8 Claims. (Cl. 25—131)

This invention relates to wall form systems and particularly to combined metal and wood forms such as are used in concrete and cement pouring operations.

Presently known wall form systems generally fall into the all wood or combined metal and wood construction. All wood forms have proven unsatisfactory because of their short span of usefulness and their high cost of construction. In addition, wooden forms increases in weight due to their tendency to absorb moisture when exposed to the elements.

Wood and metal forms as heretofore constructed have been heavy to handle, expensive to manufacture and subject to damage when being stripped from the finished wall. In addition, a wide variety of complicated ties and fastening accessories have made the metal and wood form difficult and expensive to erect.

Accordingly, it is an object of the present invention to provide a combined metal and wood form system which will be lighter per square foot than existing forms.

Another object of the present invention is to provide a wall form system which is capable of being erected by relatively unskilled labor.

An object of the present invention is to provide an inexpensive wall form system.

Still another object of the present invention is to provide a wall form system requiring a minimum number of components for assembly.

An object of the present invention is to provide a wall form system capable of numerous reuses without damage to the form panels.

A further object of the present invention is to provide a wall form system using a straight rod type tie.

An object of the present invention is to provide a wall form system which will result in a smooth pouring face on the finished wall.

A further object of the present invention is to provide a wall form system which may be stripped easily without damage to the form structure.

Another object of the present invention is to provide a wall form system which may be handled in large sections by cranes.

A feature of the present invention is its use of single frame elements which cooperate to reinforce, space, and secure adjacent form panels.

Another feature of the present invention is its use of easily installed and removed stiffener members.

Still another feature of the present invention is its use of straight rod type ties which may be inserted or removed after the forms are erected.

A further feature of the present invention is its use of a combined tie engaging form locking accessory.

A feature of the present invention is its use of a novel stripping tool which prevents damage to the form.

The invention consists of the construction, combination and arrangement of parts, as herein illustrated, described and claimed.

In the accompanying drawings, forming a part hereof is illustrated one form of embodiment of the invention, in which drawings similar reference characters designate corresponding parts, and in which:

FIGURE 1 is a somewhat isometric view of a portion of a complete wall form assembly made in accordance with the present invention.

FIGURE 2 is a fragmentary exploded view on an en-

2

larged scale of the panel supporting elements, shown in FIGURE 1.

FIGURE 3 is a sectional view taken on line 3—3 in FIGURE 1, showing the operation of the tie and tie securing accessory.

FIGURE 4 is a somewhat isometric view on an enlarged scale of the liner securing hooks and tie and panel securing members of the present form system with certain parts removed and certain elements shown in a somewhat exploded form for the purpose of clarity.

FIGURE 5 is a fragmentary view taken on line 5—5 in FIGURE 1.

FIGURE 6 is a fragmentary view taken on line 6—6 in FIGURE 1.

FIGURE 7 is a fragmentary view in vertical section taken on line 7—7 in FIGURE 1.

FIGURE 8 is a fragmentary view of a tie rod made in accordance with the present invention.

FIGURE 9 is a view in side elevation of the stripping tool showing the manner in which the tie rod and frame are engaged for stripping purposes.

FIGURE 10 is a view somewhat similar to FIGURE 9 showing the form pulled away from the poured concrete by the stripping tool.

Referring to the drawings and specifically to FIGURES 1 and 2, 20 indicates a wall form assembly consisting of a series of panels 21, secured together in side by side abutting relationship on opposite sides of an area into which concrete or cement is to be poured. The panels 21 are held in fixed spaced relationship by means of ties 22 which extend across the pouring area as shown in FIGURE 1.

It will be seen from an examination of FIGURE 1 that each of the panels 21 consist of a panel face member 23 made of a sheet of any suitable continuous material such as plywood, hard board or the like, and a supporting frame 24. It is important that the panel face material be waterproof and for this purpose the plywood may be coated on all surfaces with any of the well known plastic type coating materials.

A frame 24 is secured to the back of each of the panel face members 23, and in the present invention serves not only as a reinforcing member for the panel face member 23 but also performs other functions hereinafter more fully described. The frame 24 consists of vertical members 25 and horizontal members 26. The horizontal members 26 as best shown in FIGURE 2, are cut away as indicated at 27 to receive therein one flange of the substantially angle iron shaped vertical member 25. The horizontal member 26 is further provided with inwardly bent plates 28 at each end thereof by means of which the horizontal and vertical members are secured together.

In order to prevent concrete or cement from falling between the adjacent panels, spacer plates 29 are secured at the top and bottom of the vertical members 25 as shown in FIGURE 2. The construction of the vertical and horizontal members is substantially the same in that they are made of elongated sections of angle iron shaped steel one of the flanges of which is provided with a series of rectangular shaped openings 30 and outwardly extending embossings 31. The openings 30 serve as the engagement points for the accessories which contribute to combining the panels into a wall form assembly. The embossings 31 serve to space adjacent panels from each other in order to permit ties 22 to be inserted therebetween. As shown in FIGURE 1, the ties 22 are slipped through transverse grooves 33 which are provided in the edges of the panel face members 23. The frame 24 is also spaced from the edge of the panel face members a distance equal to the depth of the grooves 33. When adjacent grooves are brought into registration they provide a circular opening to receive the ties 22.

The vertical and horizontal frame members 25, 26, are secured at their ends by means of bolts 32 which are slipped through the holes 34, 35, provided in the vertical members 25 and plates 28, 29. The plates 29 are suitably countersunk to receive the heads of the bolts 32 so that a flat surface is presented on the adjacent plates 29.

The panel face members 23 are secured to the frame flanges 35 by means of extremely flat headed bolts 36, best shown in FIGURE 3. These bolts, commonly known as elevator bolts, are made with a large thin head which when pulled tight sink into the panel face member and form a flush surface. The bolts 36 are slipped through holes in the panel face member 23 which are drilled in register with holes 37 provided in the flange 35. It has been found that three such holes on each of the vertical edges of the panel are sufficient to secure the panel face member to the frame.

In the panel 21 shown in FIGURE 1, the standard 4' x 8' plywood sheet has been used as a panel face member. For the purpose of structural rigidity, the frame of this panel is formed with two vertical members 25 secured in abutting relationship at the center of the panel. The vertical members 25 are secured at their tops and bottoms to the horizontal members 26, in the manner hereinabove set forth. Holes (not shown) are drilled in the panel face member 23 in register with the space between the vertical members 25 at the center of the panel to receive therethrough ties 22. As shown in FIGURE 1 the ties 22 extend beyond the vertical members 25 a short distance so that they may be grasped by other parts of the wall form assembly hereinafter referred to as accessories.

Horizontal stiffeners 38 are required between the vertical frame members 25 in panels such as the 8' high panels shown in FIGURE 1. The stiffeners are of angle iron cross-sectional shape and fit between the vertical members 25. The stiffeners 38 are provided with outwardly extending tabs 39, 40, which slide into the rectangular opening 30 in the vertical members 25. The tabs 39 is somewhat longer than the tab 40, and a clearance 41 is provided between the end of the stiffener 38 and the vertical member 25 adjacent thereto. By reason of the tab construction and the clearance 41, the stiffeners can be inserted or removed from the wall panel at any time. Accordingly, as many stiffeners as are required can be inserted merely by slipping the tab 39 into an opening 30, sliding it to the end of the clearance 41 and then sliding the opposite tab 40 into a similar opening in the opposite vertical member 25. Thereafter, a nail 42 may be slipped through a small hole 43 in the stiffener 38 which is provided adjacent the vertical member 25 and through the larger of the tabs 39, so that the stiffener 38 cannot be moved laterally within the wall form. By reason of the easy application of the stiffener 38, the entire panel may be assembled or carried before the application of the stiffeners. The panel is thus much lighter to handle than would be similar devices wherein the stiffeners are permanently secured to the vertical members.

As shown in FIGURE 6, the embossings 31 on the horizontal members 26, at the top of the panel 21 serve to space panels which may be placed above the first row of panels the desired distance from each other to receive therethrough ties 22 or stub ties 44 such as are shown in FIGURE 7. The embossings are formed along the inner edge of the outwardly extending flange.

The stub ties 44 consist of short bar-like members having a very flat head 45 on the pouring end of the tie and a flattened portion 46 spaced from the opposite end of the tie 44. Holes are drilled in the panel face or grooves are made in the panel edges in the manner hereinabove described to receive the stub ties 44.

Tie securing accessories hereinafter more fully described in connection with FIGURE 4 engage the stub ties 44 at the flattened portion 46 for the purpose of securing the wall form elements together.

Referring to FIGURE 4, wherein a somewhat enlarged

fragmentary portion of the wall form assembly is illustrated, it will be seen that the abutting vertical members 25 are secured together by means of an accessory 47, hereinafter referred to as the locking accessory. The locking accessory consists of a flat plate 48 having a bifurcated portion 49 at one end thereof. The bifurcated portion 49 is disposed at substantially right angles to the plate 48 and is adapted to clamp the abutting vertical members 25 within the opening 50 of the bifurcated portion 49. Bevels 51 are provided on each side of the opening 50 to cam the ends of the vertical members 25 together as they are being forced into the opening 50. The plate 48 is also provided with an outwardly extending ear 52 opposite the bifurcated portion 49. The ear 52 lies in the plane of the plate 48 and an elongated slot 53 extends from the plate 48 into the ear portion 52.

A captive key member 54 is slidably carried within the slot 53 and is held therein by a bent over portion 55 at one end thereof.

The key 54 is somewhat L shaped and terminates in a tapered wedge 56 which is received within one of the openings 30, of the vertical members 25. The key 56 is also provided with a transverse bore 57 through which a nail 59 may be dropped after the key has been slipped through the abutting vertical members 25, to lock the key in place.

The locking accessory 47 is also provided with a key-hole slot 59, into which a tie 22 or stub tie 44 may be inserted. The narrow portion of the slot 59 is of a size which will accommodate the flattened portions 46, 69 of the ties and the large portion of the slot 59 is somewhat larger than the size of the ties so that they may be slid therethrough.

Where it is desired to use liners in conjunction with the wall form assembly, they are secured to the panels in the manner shown in FIGURE 4. For this purpose a liner clamp 60, together with a captive bar 61 and wedge 62 is employed. The bar 61 is provided with a slot 63 at its outer end and a laterally extending pin 64 spaced from its inner end. The bar 61 is made of steel having the same angle iron shape heretofore described in connection with the vertical and horizontal members. The slot 63 receives therethrough the wedge 62 which is doubled back upon itself as shown at 65 to prevent the wedge from falling out of the slot 63. The wedge 62 bears against the outside of the liner clamp 60 so that as it is driven into the slot 63 it forces the clamp 60 into holding engagement with the liners 66. It will be understood that the pin 64 must be slipped into one of the openings 30 in the vertical members 25, before the wedge 62 is driven against the clamp 60. The liners 66 may be made of lengths of 2" x 4" lumber in accordance with the well known procedure in the wall form art. The liners 66 are disposed on the top and bottom of the bar 61 and are embraced by the liner clamp flanges 80.

When it is desired to remove the liners it is merely necessary to strike the bent over portion 65 of the wedge 62 to drive it upwardly through the slot 63 until the liner clamp 60 becomes loosened. The bar 61 may then be slid laterally to disengage the pin 64 from the openings 30. Thereafter, the liner clamp assemblies may be removed and the liners separated from the wall form system.

In erecting wall form systems it often becomes apparent that additional ties are required at certain portions of the form for strengthening purposes. Often ties are left out by mistake and it becomes important to insert them before pouring begins. In accordance with the present invention there has been provided a tie, best shown in FIGURE 8, which can be inserted in the wall form system or removed therefrom without disassembling the panels previously erected. This tie 22, is made of a length of steel having a substantially circular cross-section and an overall dimension which will permit the tie to extend beyond the frame members 25, 26. The tie 22 is also

notched as indicated at 67 to form a weakened point whereby the tie may be broken back within the concrete wall after hardening. In this manner the opening made by the tie in the wall can be covered by means of cement in the well known manner. The tie 22 is flattened as indicated at 68 in FIGURE 8, to prevent the tie from rotating within the poured wall when it is sought to break the tie as hereinabove described. The tie 22 is broken by means of a tool such as a wrench (not shown) which engages the tie at a flattened portion 69 spaced from the outer ends of the tie. The flattened portion 69 forms a button 70 on the ends of the tie which is used to couple the tie to the frame of the panel. It will be noted that the tie 22, although provided with flats, 68, 69, is still of an overall diameter such that it can be slipped through the openings formed by the grooves 33 in the panel face members 23 and the space between adjacent frame members of the panels 21. In this manner, ties may be inserted or removed at any time prior to pouring the concrete without disturbing the wall form assembly 20. In addition, the ties 22 may be broken back within the finished concrete wall without disassembling the wall form assembly merely by removing the locking accessory and twisting the projecting end of the tie 22 as hereinabove described. The wall form assembly 20 may be held together by means of bolts 71, best shown in FIGURE 4. The bolts 71 are slipped through adjacent openings 39 in the vertical and horizontal frame members so that the wall form assemblies can be moved in one piece by cranes. It will be seen that after a large section of wall form panels so held together are moved to a new location, ties 22 can be slipped through and between the panels for further pouring operations.

From the foregoing, the assembly and use of wall form systems will become apparent. When it is desired to fabricate the panels it is merely necessary to take a standard piece of board such as a 4' x 8' piece coated plywood, drill the holes in the face to accommodate the bolts 36 and bolt the frame members 23, 26, to the back of the plywood. The frame members will be spaced inwardly from the edge of the plywood as hereinabove described, to permit grooves 33 to be either cut or hammered into the edge of the plywood a depth sufficient to receive the ties 22 therethrough. A series of panels 21 are then erected as shown in FIGURE 1 on either side of the footings (not shown) and may be secured thereto in the well known manner. With the panels 21 in place the ties 22 can be slipped through the assembly at the desired location and the locking accessories 47 applied to the ends of the ties 22. The locking accessories are applied to the ties 22 by slipping the ends of the ties through the enlarged portion of the keyhole slot 59. Thereafter the accessory 47 is cammed inwardly so that the opening 50 pulls the opposed edges of the frame member together in abutting relationship. The accessory is then moved down along the frame members and the tie slipped upwardly in the keyhole slot 59, which slot bears against the flattened portion 69 of the tie 22. When the accessory 47 has been driven down a distance far enough to bring the ends of the key 54 in line with an opening 39 in the frame, the key 54 is slid laterally within the slot 53 until the bore 57 in the wedge 56 extends beyond the frame members. A nail 58 is then dropped into the bore 57 to lock the entire assembly into place. This operation is repeated wherever it is desired to secure a tie and frame together.

Liners are next applied to the assembly by slipping the pin 64 of the liner clamp assembly 60, into the registered openings 30 in the vertical frame members 25. As shown in FIGURE 4, the bar 61 of the liner clamp assembly is cut away as indicated at 72, to form a bearing surface which rests upon the outer edge of the vertical frame members 25. The inner end of the bar 61 will bear against the inner flange of the vertical members and the entire liner clamp assembly will thus be held in place and extend outwardly from the panels 21. The liners 66 are

next brought to bear against the top and bottom of the bar 61 and the liner hook 73 moved inwardly until it embraces the liners 66. Thereafter, the wedge 62 is driven down until a tight engagement is made between the liner clamp assembly 60 and the liners 66 and panel frame. This operation is repeated until all of the liners are secured to the panel form structures.

The stiffeners 38 may next be inserted in the wall frame assembly at those places and in sufficient quantity to provide the strength where needed. Since the stiffeners are not secured to the frame as a permanent part of the construction they may be located at those intervals where the greatest pressure is exerted by the poured concrete. It will be apparent, that the greatest pressure is exerted adjacent the lower portion of the wall form assembly and that less pressure is applied nearer the top. Contrary to previously known wall form assemblies which have stiffeners disposed at uniform intervals over the entire panel, the present invention will enable an asymmetric disposition of the stiffeners 38 which will provide the greatest amount of strength where needed.

The stiffeners are slipped in place in the manner hereinabove more fully described and locked by means of nails 42 slipped into the holes 43 which are provided adjacent the longer tabs 39. It will be noted from an examination of FIGURE 5 that the tabs are embossed as indicated at 74 to impart additional strength thereto. It will be understood that the force applied to the stiffeners by the poured concrete will be normal to the face of the panel and that this force will be directed in the plane of the tabs 39, 40, and not normal thereto.

After the concrete or cement has been poured the locking accessories may be removed by slipping the nail 58 out of the opening 57 and sliding the key 54 out of the opening 30. The locking accessory 47 can then be driven upwardly by means of a hammer or similar tool until the tie 22 can be slipped out of the keyhole slot 59. The tie 22 can then be broken back by means of a wrench which applies a twisting force to the ends of the tie. The liners may be removed in a manner heretofore described and the entire wall form assembly 20 (if bolted together) may be moved as a single unit to the next pouring station.

However, before the wall form assembly can be moved and before the ties are broken back it is important to break the panels 21 away from the face of the poured concrete. In FIGURES 9 and 10 there is shown a panel separating tool for use in connection with the present form assembly. The tool 75 consists of a substantially Z-shaped bar 76, having an outwardly extending pin 77 at one end thereof and a tie end receiving slot 78, spaced from the top of the bar 76. The lower portion of the bar 76 consists of a handle member 79 by means of which the tool is operated. Where it is desired to strip the form from the poured face 81, the locking accessory 47 is removed and the pin 77 slipped into openings 39 in the adjacent frame members 25. The slot 78 is slipped over the end of the tie 22 and the handle 79 driven downwardly in a direction of the panel as shown in FIGURE 10. The tool 76 thereupon acts as a cam to pull the frame and the panel face member 23 free of the surface 81 of the concrete whereupon it can be removed with ease either by hand or by means of cranes. It will be understood that once the wall form assembly 20 is loosened from the pouring face 81 it may be placed up against the face for the purpose of breaking the ties 22 back as hereinabove described.

From the foregoing it will be seen that there has been provided a wall form assembly system which is simple to construct and which may be made in the field from a minimum number of metal parts and flat board panels without the need for expensive welding or riveting equipment. In addition, the panels may be shipped as metal components and the panel face members purchased locally thereby eliminating a substantial element of freight costs. Since the panels may be erected without placing the stiff-

7
eners in them until just prior to pouring, individual panels are lighter to handle than corresponding prior art structures.

Having thus fully described the invention, what is claimed as new and desired to be secured by Letters Patent of the United States is:

1. A panel locking accessory for use in concrete forms which have panel face members and angular frame members with legs extending away from said panel face members, said accessory comprising a plate, a bifurcated portion extending away from said plate and adapted to engage adjacent frame members, a tie-engaging opening in the plate, a laterally extending ear on the plate, an elongated slot in the plate and ear, a captive key member slidably carried within the slot, and a wedge on the key member engageable with openings in said legs, to secure the accessory to the frame of adjacent panel structures.

2. A liner clamp assembly comprising an elongated bar of angular shape throughout a portion of its length, a laterally extending pin carried at one end of the bar, a bearing surface on said angular shaped portion of said bar, said surface being spaced from said end carrying said pin, and parallel to said pin, the opposite end of the bar having a slot, a wedge member freely carried within said slot, and a flanged liner embracing member having an opening to receive said bar and a face to be engaged by said wedge.

3. A panel stripping tool comprising a substantially Z-shaped bar, a laterally extending pin carried at one end of said bar, a handle portion at the opposite end of said bar and a tie receiving socket intermediate said pin and said handle portion.

4. A wall form system comprising spaced panels, each of said panels comprising a panel face member, a frame on one side of said member, said frame comprising L-shaped angular metal members, each having a leg lying parallel to and extending inwardly of the edges of said panel face member and a leg extending outwardly from said panel face member at substantially a right angle thereto, said last mentioned legs being spaced inwardly from the lateral edges of said panel face member, said last mentioned legs also having spaced perforations designed to mate with perforations in equivalent legs of other panels, said last mentioned legs having at intervals adjacent their outer edges V-shaped, outwardly extending indentations designed to mate with similar indentations on equivalent legs of the frames of adjacent panel structures so as to maintain said legs in parallel, spaced positions for the passage of tie rods therebetween, the lateral edges of the panel face member being notched to permit passage of the rods, a tie and panel locking accessory comprising a plate, a bifurcated portion extending away from said plate and adapted to engage adjacent frame members, a tie engaging opening in the plate, a laterally extending ear on the plate, an elongated slot in the plate and ear, a captive key member slidably carried within the slot, and a wedge on the key member engageable with said perforations in said legs extending away from said panel face member, to secure the accessory to the frame of adjacent panel structures.

5. The structure claimed in claim 4 including liners for said wall form system, a liner clamp assembly com-

8
prising an elongated bar of angular shape throughout a portion of its length, a laterally extending pin carried at one end of the bar, said pin engageable in a pair of said mating perforations in the frames of adjacent frame structures, the opposite end of the bar having a slot, a wedge member freely carried within said slot, and a flanged liner-embracing member having an opening to receive said bar and a face to be engaged by said wedge.

6. The structure claimed in claim 4 wherein said tie-engaging opening is a keyhole slot to engage one of a plurality of flattened portions of a tie spaced from the tie end, said flattened portions being selectively engageable in the said keyhole slot.

7. The structure claimed in claim 5 including panel stiffeners carried between opposed ones of said L-shaped angular metal frame members, said stiffeners comprising L-shaped angular metal body members of a length less than the space between the legs of said opposed frame members, a tab extending from each end of the body of each stiffening member, one of said tabs being longer than the other, said tabs being receivable within corresponding ones of said openings in said legs which extend away from said panel face member after said frame has been assembled, the combined lengths of the stiffener body member and said tabs being greater than said space whereby a tab may be extended through each of said outwardly extending legs, and whereby one at least of said tabs may be engaged by fastening means to hold said stiffening members in place.

8. The structure claimed in claim 6 including tie members, and wherein said tie members are provided with weakening notches inwardly spaced from flattened portions, and have tie anchoring second flattened portions between said weakening notches.
